Des. 224,473
Patented July 25, 1972

224,473

BICYCLE STEERING POST

Robert F. Humlong, Maysville, Ky., assignor to Wald
Manufacturing Company, Inc., Maysville, Ky.

Filed Apr. 1, 1970, Ser. No. 22,161

Term of patent 14 years

Int. Cl. D12—14

U.S. Cl. D90—9

FIG-1

FIG-2

FIG-3

FIG. 1 is a side elevation plan view of a bicycle steering post showing my new design.

FIG. 2 is a front elevational view thereof as seen from the left side of FIG. 1.

FIG. 3 is a top plan view thereof.

I claim:

The ornamental design for a bicycle steering post, as shown.
